UNITED STATES PATENT OFFICE

135,833

DESIGN FOR A PORTABLE HEATING UNIT

Harry B. Holthouse, Chicago, Ill., assignor to Galvin Manufacturing Corporation, Chicago, Ill., a corporation of Illinois

Application October 27, 1942, Serial No. 168,623

Term of patent 14 years

To all whom it may concern:

Be it known that I, Harry B. Holthouse, a citizen of the United States, residing at Chicago, in the county of Cook and State of Illinois, have invented a new, original, and ornamental Design for a Portable Heating Unit, of which the following is a specification, reference being had to the accompanying drawings, forming part thereof, in which:

Fig. 1 is a perspective view of one side of a portable heating unit showing my new design;

Fig. 2 is a perspective view showing the top, front and other side thereof; and

Fig. 3 is a perspective view showing the top and back thereof.

The dominant features of my design reside in the portions shown in solid lines in the drawings.

I claim:

The ornamental design for a portable heating unit, substantially as shown and described.

HARRY B. HOLTHOUSE.
